WATCH BAND OR SIMILAR ARTICLE

Joseph L. Hajos, Bronx, N. Y., and Kurt Speck, Palisades Park, N. J., assignors to Jacques Kreisler Manufacturing Corporation, North Bergen, N. J., a corporation of New Jersey

Application May 5, 1953, Serial No. 24,858

Term of patent 7 years

(Cl. D45—4)

To all whom it may concern:

Be it known that we, Joseph L. Hajos and Kurt Speck, both citizens of the United States of America, residing respectively at Bronx, New York, county of Bronx, and State of New York, and Palisades Park, county of Bergen, and State of New Jersey, have invented a new, original, and ornamental Design for a Watch Band or Similar Article, of which the following is a specification, reference being had to the accompanying drawing forming part thereof.

Fig. 1 is a top plan view of a watch band showing our new design;

Fig. 2 is an edge view thereof; and

Fig. 3 is a cross-sectional view thereof taken along the line 3—3 of Fig. 2 and drawn to a larger scale.

The broken line disclosure in Fig. 1 represents leather.

The dominant feature of applicants' design resides in the portions shown in full line.

We claim:

The ornamental design for a watch band or similar article, substantially as shown and described.

JOSEPH L. HAJOS.
KURT SPECK.
